Attorney.

UNITED STATES PATENT OFFICE.

GEORGE F. ZAUN, OF SAN BERNARDINO, CALIFORNIA.

CAR-DOOR VENTILATOR.

1,353,301.

Specification of Letters Patent. Patented Sept. 21, 1920.

Application filed March 25, 1920. Serial No. 368,767.

To all whom it may concern:

Be it known that I, GEORGE F. ZAUN, a citizen of the United States, residing at San Bernardino, in the county of San Bernardino and State of California, have invented new and useful Improvements in Car-Door Ventilators, of which the following is a specification.

This invention relates to improvements in car door ventilators, and has for an object the provision of a ventilator that may be placed between a sliding door of a box car and the door jamb and which will allow air to enter the interior of the car and ventilate same.

At the present time, particularly in refrigerating cars and cars that carry perishable products, it is necessary that some means be provided to allow the air to circulate within the car, as stagnant air causes a rapid decay of fruit, vegetables, etc. In order to allow for this ventilation, ordinarily the box car door is opened slightly and cleats are nailed across the door jamb and the door, after which a Government inspector places a thin seal upon one of the strips of the door showing that the car has been inspected. Thieves or tramps desiring to steal the contents of the car will not disturb the Government seal, but will break the cleats or smash in the side of the door in order to gain access to the material stored therein. Thousands of dollars are lost annually by such acts and in order to overcome and reduce same and render access to the car a difficult matter, I have accordingly provided a ventilating means having a suitable frame covered with a foraminous material or having transverse louvers thereon, which frame is adapted to swing into position between the door and the door jamb. Means are likewise provided for holding the ventilating member either in a position coacting with the door and door jamb, or in an inoperative position, which position would be when the ventilating member is swung back against the side of the box car.

The invention has for further objects the provision of a device of the character stated, which will be superior in point of relative simplicity and inexpensiveness of construction, taken in connection with positiveness and convenience in operation, reliability and general efficiency and serviceability, as well as neatness in appearance. A further object is to provide a ventilating means which may

be attached to a box car and which will not require any material changes in the box car construction.

With the above and other objects in view, the invention consists in the novel and useful provision, formation, combination, association and interrelation of parts, members and features, all as hereinafter described, shown in the drawing, and finally pointed out in claims.

In the drawing:

Figure 1 is a fragmentary elevation of a box car with a ventilating member in position between the car door and the door jamb;

Fig. 2 is a fragmentary elevation showing a ventilating member swung to and against one side of the car, said ventilating member being inoperative;

Fig. 3 is a cross sectional view of the ventilating member, taken on the line x^3-x^3 , Fig. 2, and looking in the direction of the appended arrows;

Fig. 4 is a cross sectional view of certain elements of the ventilating member taken on the line x^4-x^4 , Fig. 1;

Fig. 5 is a fragmentary cross sectional view showing certain details of construction, and taken on the line x^5-x^5 , Fig. 1;

Fig. 6 is a perspective view of a hasp attachment used in practising the invention;

Fig. 7 is a fragmentary interior view of a box car showing certain means for holding the ventilating member in position relative to the door and door jamb; and,

Fig. 8 is a fragmentary elevation of a modification of the ventilating member.

Corresponding parts in all the figures are designated by the same reference characters.

Referring particularly to the drawing, A designates a box car, B, a ventilating member, and C means for maintaining the ventilating member in position upon the car, all of which elements are used in practising one embodiment of the invention.

The box car A which is of standard construction includes a door 1 mounted upon rollers 2, which rollers engage a rail 3 attached to the box car A. The door 1 is adapted to travel back and forth in order to permit access to the interior of the box car A through an opening 4 in said car. The door 1 is likewise provided with a hasp 5 pivotally held in position to the door by a staple 6. A staple 7 is mounted upon the door jamb 8 in such a position that a slot

9 in the hasp 5 may engage the staple when the door 1 is in a closed position, as shown in Fig. 2.

The ventilating member B includes a frame structure 10 rectangular in form, though not necessarily so, and which frame structure 10 has parallel side members 11 and 12 of a length corresponding to the length of the door jamb or stop 8, or nearly so; that is, of sufficient length so that a person could not gain access to the interior of the car by crawling over the top of the ventilating member. The side members 11 and 12 are provided with transverse louvers 13, or the ventilating member may be covered with a foraminous material 14, although it has been found that the louvers are more practicable in that more difficulty would be experienced in cutting away any portion of the ventilating member in order to gain access to the interior of the car A. In order to maintain the ventilating member B in position upon the box car A, ears 15 are joined to the ventilating member as at 16 and 17. Each ear is provided with a transverse perforation 18 which accommodates a J-shaped retaining means 19 having one leg as 20 passing transversely through a portion of the side of the car A, as shown at 21, and held in position by means of a nut 22, which nut is located on the interior surface of the car. The opposite end of the member 19 is returned as at 23 and passed through the perforation 18 in the ear 15 and into a portion of the door jamb 8 as at 24. This particular construction is brought out in detail in Fig. 5, and it will be observed that the return portion 23 does not pass entirely through the door jamb 8. The ventilating member B may be swung backwardly or forwardly as the ear 15 moves upon the member 19, the combination of the ear 15 and the member 19 forming a hinge. This particular construction only requires that a hole be bored through the sides of the box car adjacent the door portions. Thus any standard form of box car may be used without the necessity of any material changes in its construction when utilizing this ventilating member.

In order to insure that the ventilating member B may at all times be safely secured between the door jamb and the door, clamps, yokes or saddles 25 project from and are fastened to the side member 12.

Referring to Fig. 4, it will be observed that the member 25 is bifurcated so as to engage a portion of the door 1, as shown at 26.

Obviously the hasp 5 shown in Fig. 2 would not be long enough to engage both the door 1 and the door jamb 8 and still hold the ventilating member B in position between the door and door jamb. In order 65 to provide a secure locking means when the

member B is in operative position, a hasp extension 27 shown in Fig. 6 is provided, which hasp has for a portion near one end of same, as at 28, a longitudinal slot 29, while the other end has an angularly disposed extremity in the form of a T head 30, which may engage the slotted portion 9 in the hasp 5. The hasp extension 27 is of a length sufficient that when used in combination with the hasp 5 it may engage the staple 7 located in the door jamb 8 and hold the door 1 in close relation to the side member 12 of the ventilating member B.

If it is not desired to use the ventilating member B, same may be swung out of position against a side of the car door A, as shown in Fig. 2. In order to securely lock the ventilating member B against the side of the car A an additional hasp 5^a is mounted upon the door jamb 8, and as the member 27 may be disconnectedly joined to the hasps, this member is again utilized as shown in Fig. 2 to hold the ventilating member B against the side of the car A. A staple 7^a is passed through a portion of the side of the car A as at 33 so that the slotted portion of the hasp extension 27 may engage same.

Ofttimes a railroad company would not desire to bore a hole through the side of the box car A in order to accommodate the member 19. In order to still utilize the ventilating member B, I have accordingly provided said member with a link or chain 31 which is attached to the door jamb 8 in the interior of the box car A. A peg or bracket 32 is fastened to the door jamb and over which peg or bracket one link of the chain 31 may be passed.

Obviously the chain or link 31 will permit the ventilating member B to be swung into or out of position relative to the door jamb and the door of the box car in the same manner as if the member 19 were utilized.

To provide a locking means for holding the hasp or the hasp extension in a fixed relation to the staple 7, a Government official passes a thin strip of material through the eye of said staple. This strip is ordinarily made of some thin flexible material, and inasmuch as it is a penitentiary offense to break the strip, a tramp or thief probably would never in any way tamper with the hasp or hasp extension in order to gain access to the interior of the box car A. Furthermore, as the ventilating member B is ordinarily made of sheet metal, it would be a difficult matter to smash any of the louvers.

It is obvious that many changes and modifications may be made in departure from the particular description and showing of the accompanying drawing, in adapting the invention to varying conditions and require-

ments of use and service, without departing from the true spirit of the invention.

Having thus disclosed my invention, I claim and desire to secure by Letters Patent:

- 5 1. Improvements in box cars having a 65
slidable door, of a ventilating member ad-
justably mounted on the car and adapted to
be swung into position to be engaged by one
edge of the door, and means for locking the
10 door and maintaining the ventilating mem-
ber in operative position; said box car be-
ing provided with a door jamb, and the ven-
tilating member being received between the
15 door and door jamb; locking means com-
prising a pivoted hasp adapted to extend
between the car and door and over the ven-
tilating member, and means for holding the
hasp so extended.
2. Improvements in box cars having a 20
slidable door, of a ventilating member ad-
justably mounted on the car and adapted to
be swung into position to be engaged by one
edge of the door, and means for locking the
25 door and maintaining the ventilating mem-
ber in operative position; said box car be-
ing provided with a door jamb, and the ven-
tilating member being received between the
30 door and door jamb; said locking means
comprising a pivoted hasp, an extension
hasp coöoperating with said first named hasp.
3. Improvements in box cars having a 35
slidable door, of a ventilating member ad-
justably mounted on the car and adapted to
be swung into position to be engaged by one
edge of the door, and means for locking the
40 door and maintaining the ventilating mem-
ber in operative position; said box car being
provided with a door jamb, and the ven-
tilating member being received between the
45 door and door jamb; said locking means
comprising a pivoted hasp adapted to en-
gage the car and door, and catch means for
the hasp; means for coöoperating with said
50 pivoted hasp whereby when the ventilating
member is in position between the door and
jamb, the pivoted hasp may be extended in
length so as to pass over the ventilating
55 member.
4. Improvements in box cars having a
slidable door, of a ventilating member ad-
justably mounted on the car and adapted to
be swung into position to be engaged by one
edge of the door, and means for locking the
60 door and maintaining the ventilating mem-
ber in operative position; said box car being
provided with a door jamb, and the ven-
tilating member being received between the
65 door and door jamb; said locking means
comprising a pivoted hasp, an extension
hasp coöoperating with said first named hasp,
said pivoted hasp and said extension hasp
being adapted to extend between the car
and door and over the ventilating member,

and means for securing the pivoted hasp 65
and extension hasp; said securing means
comprising a member having an eye
adapted to receive the locking means.

5. The combination with a box car having
a 70
slidable door and stop for the door, of a
ventilating member mounted to swing into
or out of position between the door and stop,
and means for maintaining the ventilating
75 member either in the latter position or
against the side of the car.

6. Improvements in box cars having a 80
slidable door, of a ventilating member ad-
justably mounted on the car and adapted to
be swung into position to be engaged by one
edge of the door, and means for locking the
85 door and maintaining the ventilating mem-
ber in operative position; said box car being
provided with a door jamb, and the ven-
tilating member being received between the door
90 and door jamb; said locking means com-
prising a pivoted hasp adapted to engage
the car and door, and catch means for the
hasp; means for coöoperating with said piv-
95 oted hasp whereby when the ventilating
member is in position between the door and
jamb, the pivoted hasp may be extended in
length so as to pass over the ventilating
member; said last named means comprising
an extension hasp slotted for a portion near
one end while the opposite end has an angu-
larly disposed extremity in the form of a
T head, which T head engages a slot in said
first named hasp.

7. Improvements in box cars having a 100
slidable door and stop for the door, of a
ventilating member mounted to swing into
position between the door and stop, and
means for maintaining the ventilating mem-
ber in the latter position; said ventilating
105 member comprising a frame member pro-
vided with louvers; said means for main-
taining the ventilating member in position
comprising clamps outwardly depending
from an edge of said ventilating frame for
110 engaging said door.

8. Improvements in box cars having a
slidable door and stop for the door, of a
ventilating member mounted to swing into
position between the door and stop, and
means for maintaining the ventilating mem-
ber in the latter position; said ventilating
115 member comprising a frame provided with
louvers; said means for maintaining the ven-
tilating member in position comprising
clamps outwardly depending from an edge
of said ventilating frame for engaging said
120 door, and hinge means joining the door stop
and ventilating member whereby same may
be swung into or out of position between the
125 door and stop.

9. Improvements in box cars having a
slidable door, of a ventilating member ad-

justably mounted on the car and adapted to swing into position to be engaged by one edge of the door, or to be swung into an inoperative position against a side wall of the car; means for locking the door and maintaining the ventilating member in an operative position or in an inoperative position; said box car being provided with a door jamb and the ventilating member when in

operative position being received between 10 the door and door jamb.

In testimony whereof I have signed my name to this specification in the presence of two subscribing witnesses.
